UNITED STATES PATENT OFFICE.

JOHN N. KORVALLIS, OF LOS ANGELES, CALIFORNIA.

DESIGN FOR AN AUTOMOBILE SIGNAL.

Application filed July 30, 1928 Serial No. 27,620. Term of patent 14 years.

To all whom it may concern:

Be it known that I, JOHN N. KORVALLIS, a citizen of Greece, and a resident of Los Angeles, California, have invented a new, original, and ornamental Design for an Automobile Signal, of which the following is a specification, reference being had to the accompanying drawing, forming a part hereof.

Figure 1 is a front elevation of the signal in normal position.

Figure 2 is a bottom plan of the signal.

I claim:

The ornamental design for an automobile signal substantially as shown.

JOHN N. KORVALLIS.
